UNITED STATES PATENT OFFICE

ROY A. WEAGANT, OF DOUGLASTON, NEW YORK, AND GEORGE A. SOMERSALO, OF JERSEY CITY, NEW JERSEY, ASSIGNORS TO DE FOREST RADIO COMPANY, OF JERSEY CITY, NEW JERSEY, A CORPORATION OF DELAWARE

MEANS FOR PREVENTING RERADIATION IN ANTENNAE

Application filed January 22, 1925. Serial No. 3,980.

The object of this invention is the provision of new, simple and inexpensive, but positive, means for preventing oscillations generated by a radio receiving set from being reradiated by the antenna.

A further object of the invention is to provide means for affording two or more input circuits to an electrical instrumentality, e. g., a three-electrode thermionic vacuum tube or audion, which can be independently severally adjusted without any interaction or mutual effect therebetween.

The invention consists substantially in the construction, combination, location and relative arrangement of parts, as well as in the circuit arrangement employed in connection therewith, all as will be more fully herein-after set forth, as shown by the accompanying drawings and finally pointed out in the ap-
20 pended claims.

Referring to the drawings:—

Fig. 1 is a diagrammatic illustration of a simple one-tube regenerative detector with our invention applied thereto.

25 Figs. 2 and 3 show modified arrangements embodying our invention.

The same part is designated by the same reference character wherever it occurs throughout the several views.

30 The disadvantage, annoyance and disturbance incident to the employment of radio receiving circuits which generate oscillations and, through the receiving antenna, radiate the same, are so well recognized that even the advantages to be derived from the amplification properties of a regenerative circuit are fast being sacrificed because thereof. It is, of course, well known that a radiating antenna located adjacent to or in

35 the near proximity of another antenna has such a disturbing effect thereon as to render the reception of broadcast news and music impossible, or, if not impossible, far from pleasant to hear. The disturbing effect is so well recognized that in certain parts of the world legislation has been proposed and passed prohibiting the use of regenerative circuits, for this reason.

40 Other circuits, however, which are not of the strictly regenerative type, especially the

multi-tube circuits, set up oscillations which may be equally disturbing, due to various types of coupling between the respective circuits of the respective tubes, whereby, while a regenerative connection is not employed, a regenerative effect is secured. 55

It is among the special purposes of our present invention to provide an exceedingly simple arrangement or unit for the prevention of oscillations set up in the receiving circuits or equipment from being radiated from the receiving antenna. 60

The nature of the invention is such that it may be utilized as a unit, or unitary construction, and employed as an accessory to existing receiving sets. The commercial advantage of this will be readily appreciated inasmuch as but at slight expense the accessory may be added to existing equipment. 65

Furthermore, the invention is of such a 70 nature that it can be applied to any receiving set, irrespective of the number of tubes it employs or the type of circuits employed therewith. In other words, the invention may be employed with a single tube regenerative receiver as efficiently as it may be with any other number. 75

Finally, while the invention, as above stated, may be embodied in a very easily connected accessory to existing radio sets, it may 80 be incorporated in the construction of new sets, irrespective of size or circuit, at minimum additional expense and practically no alteration of design.

In the co-pending application of Roy A. 85 Weagant, (one of the inventors hereinabove identified), Serial No. 752,835, filed November 29, 1924, for Radio signaling systems, is shown and described a means for the prevention of generation of oscillations in a multi-tube circuit due to inherent capacity or coupling, etc., wherein the phase relation of the circuits is controlled to effect a balance between the circuits and thus prevent the generation of oscillations. 90

95 Referring to the drawings, reference character 1 designates an ordinary type of thermionic vacuum tube, including the filament electrode 2 and the plate electrode 3, with the grid electrode 4 interposed therebetween. 100

The grid electrode 4 is connected to the filament electrode through a network to which it is connected at the point 5, one branch including the inductance 6 shunted by variable capacity 7 forming the tuned input or oscillation circuit, the opposite terminals of which are connected to the point 8 of the network through condensers 9 and 10 respectively. The plate electrode is connected 10 through the tickler coil 11, "B" battery 12 and telephone receiver 13 to the filament. The telephones are preferably shunted by a capacity 14 which, as is generally the case, may be the capacity of the telephone cords, 15 if desired. The antenna 16 is connected to the point 17 of the network, which point is connected to the points 15 and 5 of the network through the condensers 18 and 19 respectively. By so relating the capacity values 20 18, 19, 9 and 10 in any of the well-known ways, so as to effect a Wheatstone bridge or similar type of network, the nodal points 17 and 8 are totally unaffected by oscillations in any of the circuits of the vacuum tube 1. 25 While we have shown the objects of the invention for the purpose of illustration as secured by the employment of capacities for the electrical elements of the grid or network, we wish it to be understood that any 30 other type of electrical elements, such as inductances, resistances, or combinations of inductances, resistances and capacities, may be employed.

It will be seen, therefore, that the balanced effect is totally unaffected by any type of circuit employed with the antenna, and this is true wholly independently of the number of tubes employed. It is, of course, possible to put a variable inductance 20, such as a 35 variometer or any other type of inductance, across the nodal points 17 and 8 of the network without in any way affecting the input tuning 6, 7, or without in any way being affected by the input tuning.

It will be readily appreciated that this affords a simple and, as we believe, the only possible way of separate tuning with any regenerative circuit employing a single tube, without disturbing reactions. If desired, the 40 variable inductance 20 may be placed in series with the network, either between the network and ground or between the network and the aerial. To illustrate this feature Fig. 3 is shown with the variable inductance 20 connected between the antenna and the nodal point 17.

While in Fig. 1 we have shown the invention as applied to a radio receiving set, we 45 do not desire to be limited or restricted in this respect as the invention forms an ideal form of coupling between tubes so that it is possible to independently tune the input and output circuits without any reactions; i. e., 50 permit maximum transference of energy

with selectivity and absence of reactive effects.

Having in mind that the input circuit of any thermionic vacuum tube would be connected between the points 5 and 8, it will be apparent that the entire assembly forms an exceedingly simple but nevertheless positive preventer of radiation in the antenna of oscillations generated in the receiving circuit, and at the same time provides an accessory to existing sets irrespective of circuit arrangement. 70 75

One very important feature of our present invention is the fact that by the use of the radiation preventer it is possible to utilize a single aerial for any number of receiving sets, and the practicability and commercial value thereof will be readily apparent. Particularly in congested districts, such as in large cities, where a number of people reside in 80 apartments, instead of necessitating independent aerials for each apartment, as heretofore, a single aerial for each building, for example, may be provided, with attachment there-to by as many of the dwellers in the building 85 as desired. 90

It will be seen from the foregoing that it is possible by means of our invention to employ two or more input circuits to any electrical instrumentality or system, such, for example, as an audion system, and that variation of the electrical constants of one of these input circuits can be effected without in any way affecting the others in any manner whatsoever. The great value of being thus able to 100 employ a plurality of input circuits independently tunable or adjustable, as well as the advantages that can be obtained thereby, will be readily apparent to those skilled in the art. 105

Having now set forth the objects and nature of our invention, and having shown and described structures embodying the principles thereof and one application thereof, to which, however, as pointed out, we do not 110 desire to be limited or restricted, what we claim as new and useful, of our own invention, and desire to secure by Letters Patent, is:—

1. The combination with a three electrode vacuum tube having a controlling system and 115 a controlled system of a balanced capacity network having two sets of nodal points, an input circuit connected across one set of nodal points, a tuned circuit connected across the other set of nodal points, an inductance for associating one of said systems with said tuned circuit and a circuit including the other of said systems and one arm of said network. 120

2. The combination with an electron discharge device having a controlling circuit and a controlled circuit, of a balanced capacity network having two sets of nodal points, an antenna ground circuit connected across one set of nodal points, a variably 125 130

tuned circuit connected across the other set of nodal points, means for inductively coupling the controlled circuit of said electron discharge device with said tuned circuit, and 5 connections including the controlling circuit of said electron discharge device and one arm of said network.

3. The combination according to claim 2 in which the controlling and controlled circuits 10 are coupled through said inductance and said tuned circuit to provide a regenerative feed back.

4. The combination according to claim 2 in which each arm of the network consists 15 substantially entirely of a capacity.

In testimony whereof we have hereunto set our hands on this 17th day of January, A. D. 1925.

ROY A. WEAGANT.
